United States Patent Office

Des. 197,742
Patented Mar. 17, 1964

197,742

PROJECTED IMAGE VIEWER OR SIMILAR ARTICLE

Eugene Martinez, Irvington on Hudson, and Marvin
Kapilow, Croton on Hudson, N.Y., assignors of one-
third to Robert H. Reibel, Croton on Hudson, N.Y.

Filed Aug. 16, 1962, Ser. No. 71,307

Term of patent 14 years

(Cl. D61—1)

FIG. 1 is a top front perspective view of a projected image viewer or similar article showing our new design;

FIG. 2 is a bottom rear perspective view thereof;

FIG. 3 is an enlarged front elevational view thereof;
and

FIG. 4 is an enlarged rear elevational view thereof.

The dominant features of our new design are shown in solid lines in the drawing.

We claim:

The ornamental design for a projected image viewer or similar article, substantially as shown and described.
